UNITED STATES PATENT OFFICE.

FRANK J. HAUMAN, OF BAY SHORE, NEW YORK.

AIRPLANE-ENGINE MUFFLER.

1,318,996.

Specification of Letters Patent.

Patented Oct. 14, 1919.

Application filed June 5, 1918. Serial No. 238,334.

To all whom it may concern:

Be it known that I, FRANK J. HAUMAN, a citizen of the United States, and a resident of Bay Shore, in the county of Suffolk and State of New York, have invented a new and Improved Airplane-Engine Muffler, of which the following is a full, clear, and exact description.

This invention relates to mufflers for propelling engines for airplanes, automobiles and the like, which depends for its successful operation on the production of a suction through the exhaust pipe of the engine, thus eliminating back pressure while effectively muffling the sound.

The invention has for its general objects to provide a comparatively simple and inexpensive muffler which includes a suitably shaped chamber open at its rear for the outlet of the exhaust gases, and having a plurality of fans rotatably mounted in the chamber at a point behind that where the exhaust pipe connects with the chamber, whereby the rotation of the fans draws off the exhaust gases.

A more specific object of the invention is the provision of a windwheel at the front of the muffler for driving the fan blades within the same, such wheel being driven by air pressure due to the forward motion of the vehicle on which the muffler is mounted.

With such and other objects in view, the invention comprises various novel features of construction and arrangement of parts which will be set forth with particularity in the following description and claims appended hereto.

In the accompanying drawing which illustrates one embodiment of the invention and wherein similar characters of reference indicate corresponding parts in all the views,

Figure 1 is a central vertical section of the muffler;

Fig. 2 is a detail view of one of the fan-shaped bearings; and

Fig. 3 is a transverse section on the line 3—3, Fig. 1.

Referring to the drawing, 1 designates the cylindrical body of the muffler which has its front end closed by a head 2 shaped on stream-line design, and the rear of the body has a conical nozzle or outlet 3. Con-

nected with the interior of the body at a point adjacent the front is an exhaust pipe 4 from a gas engine, there being a cowl 5 extending into the body, whereby the exhaust gases are more effectively drawn to the rear.

Extending through the body is an axially disposed shaft 6 on the rear portion of which are mounted a plurality of fan elements 7 axially spaced apart and located to the rear of the exhaust pipe 4. The shaft, which has its forward end 8 extending out of the head 2, is mounted in ball bearings 9 in spiders 10 fastened in the ends of the body 1. On the front end of the shaft is a windwheel 11 against which the air acts as the vehicle moves forwardly, whereby the shaft 6 is rotated at a high speed, so that the fans within the body 1 will tend to produce a vacuum into which the exhaust gases flow. The blades of adjacent fans are staggered so that the products of combustion must pass through a greater number of passages that assist materially in muffling the sound while at the same time eliminating back pressure.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A muffler for airplane engines and the like, comprising a body open at its rear and closed at the front and having an exhaust inlet at the side, a shaft extending longitudinally of the body and out of the front thereof, fans on the rear portion of the shaft, and a windwheel on the front end of the shaft for rotating the same.

2. A muffler for airplane and other engines, comprising a body having a closed

pointed forward end, a windwheel at the front of the body, a suction-producing fan within the body and driven by the windwheel, and an engine exhaust connection with the body at a point in front of the said means.

3. A muffler for airplane and other engines, comprising a body having a closed

pointed forward end, a windwheel at the front of the body, a suction-producing fan within the body and driven by the windwheel, an engine exhaust connection with the body at a point in front of the said means, and a tapering nozzle connected with the rear end of the body. 10

FRANK J. HAUMAN.
